UNITED STATES PATENT OFFICE.

ARCHIE L. BOUGHAN, OF CANTON, ILLINOIS.

FRAME FOR STACKING STRAW.

1,145,111.

Specification of Letters Patent.

Patented July 6, 1915.

Application filed January 27, 1915. Serial No. 4,781.

To all whom it may concern:

Be it known that I, ARCHIE L. BOUGHAN, a citizen of the United States, residing at Canton, in the county of Fulton and State 5 of Illinois, have invented certain new and useful Improvements in Frames for Stacking Straw, of which the following is a specification.

This invention relates to receptacles for 10 receiving and protecting the straw from threshing machines, and adapted to receive the straw from the stacker conveyer of the threshing machine and retain the same in uniform shape, and protect the straw from 15 damage or from being blown about by the wind.

Another object of the invention is to provide a simply constructed device which may be increased or decreased in size as required, 20 and constructed in sections whereby the device may be enlarged by adding sections thereto.

Another object of the invention is to provide a device which may be dismembered 25 for transportation or storage and quickly erected wherever required.

With these and other objects in view the invention consists in certain novel features of construction as hereafter shown and described, and then specifically pointed out 30 in the claims; and in the drawings illustrative of the preferred embodiment of the invention Figure 1 is a plan view of the improved device; Fig. 2 is an elevation of the 35 same; Fig. 3 is an enlarged end view; Fig. 4 is a side elevation on the same scale as Fig. 3, illustrating the construction more fully. In Figs. 3 and 4, the wire netting panels are shown in position while in Figs. 40 1 and 2 the wire netting panels are removed; Fig. 5 is a plan view of a portion of the frame of one of the terminal sections, illustrating its construction; Fig. 6 is a side view of the parts shown in Fig. 5; Fig. 7 45 is a detail of a portion of the frame, illustrating the arrangement of one of the tie braces or rods; Fig. 8 is a plan of the parts shown in Fig. 7.

Corresponding and like parts are referred 50 to in the following description and indicated in all the views of the accompanying drawings by the same reference characters.

The straw conveyer or discharge portion 55 of a threshing machine is usually arranged to swing upon a turn-table and deposit the straw in a semi-circle, thus forming a semi-

circular stack. This is true whether the conveyer is of pneumatic form or of the slatted belt form, and the improved device is adapted equally for use in connection with 60 any of the ordinary straw discharge devices of a threshing machine. When the straw is deposited in a semi-circular stack it is liable to be scattered by the wind, becomes 65 loosened, and is exposed to the elements and thus deteriorated.

The improved device is designed to retain the straw in a compact condition and in symmetrical form so that it is protected 70 from injury by the elements or from being blown away by the wind.

The improved device comprises a receptacle for the straw constructed of an open metal frame work, preferably of gas or steam piping, and galvanized or otherwise protected from corrosion. The frame work is 75 preferably formed in angular sections, corresponding when united to the sweep of the straw delivering mechanism of the thresher, and adapted to be united end to end to increase 80 or decrease the length of the receptacle, and likewise arranged to be adjusted laterally to increase or decrease the width of the receptacle. The receptacle is likewise suitably braced and supported to prevent collapse when empty and likewise to prevent outward displacement by the pressure of the straw when full. The receptacle is preferably formed widest at the bottom with the 85 sides converging toward the top and with the outer portions of the sections highest to facilitate the entrance of the straw from the conveyer.

The improved apparatus includes inwardly inclined terminal supporting members 95 10 and intermediate supporting members 11. Any required number of the intermediate supporting members may be employed depending upon the number of the sections of the apparatus, but for the purpose of illustration two of the intermediate supporting members are shown, thus providing for a structure having three sections or portions. The members 10 are provided with a plurality of sleeves 12 spaced any 100 suitable distance apart, depending upon the length of the members 10. Generally the members 10 will be from 14 to 16 feet in length, and the lowest sleeves 12 of each of the members 10 will be located a short distance above the ground, indicated conventionally at 13, and the members 10 and 11 105 110

are embedded for a short distance in the ground, as indicated at 14, to increase the stability of the device. Each of the sleeves 12 at one side is provided with a single ear, indicated at 15, to receive a pivot pin 16. Mounted for rotation upon each of the pivot pins 16 by spaced ears is a coupling head 17, in which a section of piping 18 is slidably received. Each of the sleeves 12 at the 10 opposite side is provided with a socket 19 in which the sections of piping 18 are received and secured in place by a bolt 20 or other suitable fastening device. The pipe sections 18 are each provided with a plurality of apertures 22 spaced apart to receive a holding bolt 23, engaging through the coupling head 17, so that the pipe sections 18 may be adjustably coupled to the head. By this means, each opposite pair of 20 the members 10 may be adjusted toward and away from each other to increase or decrease the width of the device. The members 10 and 11 at one side of the structure are longer than the corresponding members 25 at the other side, as shown at 24, the members 10 terminating in elbows 25. The sleeves 12 are also each formed with a lateral socket 26.

The intermediate supports 11 at one side 30 are each provided with a plurality of sleeves 27 each having a lateral socket 28 to receive one end of sections of piping 29, the other ends of the latter pipe sections being received in the lateral sockets 26 of the 35 sleeves 12 and held in place by clamp bolts or like devices 30-31. Each of the sleeves 27 is also provided with a lateral socket 32 in which the terminals of pipe section 33 are received and secured therein by clamp bolts 40 34. At their upper ends the members 11 at one side are provided with sleeves 36 each having lateral sockets 37 to receive pipe sections 38, which are held in place by clamp bolts or like devices 39. The outer ends of 45 the pipe sections 38 are received in the elbows 25 and secured in place by clamp bolts or like devices 40. The pipe sections 29-38 at one side of the structure are wider than at the other, so that when the device is assembled it will assume the form shown in 50 Fig. 1, and may be lengthened to any required extent by simply inserting additional members 11, 29 and 38 and their attachments, as will be obvious. Each opposite 55 pair of the members 11 is provided with one or more ears 41 to receive coupling heads 42 pivotally united at 43 to the ears and connected by stay rods 44, to prevent the collapse of the frame while being used.

60 Each section of the improved structure will be covered with screen material of rela-

tively coarse mesh, and preferably formed in a plurality of panels and detachably supported from the pipe sections. Each of the panels of screen material is formed with 65 relatively heavy side members 45 to which the screen material, indicated at 46, is connected, so that the panels may be rolled up when not in use, or for shipment or storage. The upper pipe members of the supporting 70 frame are provided with devices such as hooks 47 to detachably support the screen panels. One of the end screen panels is formed with an opening represented at 48, to provide access to the persons who are to 75 "trim" the straw within the structure. By this arrangement, it will be obvious that a simply constructed device is produced which may be increased or decreased in size, both laterally and longitudinally and thus adapt 80 the device to the size of the stack to be formed.

The brace rods 44 may be readily uncoupled when not required. The wire screen panels may be of any required size and 85 shape and adapted to be extended to correspond to the frame work by simply adding panels if the frame work is enlarged or removing panels if the frame work is reduced in size. The members 45 of the screen 90 panels may be bolted or otherwise secured to the intermediate pipe members 18 and 29 at suitable points.

Having thus described the invention, what is claimed as new is:

1. In an apparatus of the class described, a frame formed of a plurality of sections constructed with horizontal and vertical members, means for uniting the horizontal members of the sections, a plurality of panels comprising rigid side bars and screen material connected to the side bars, and means for suspending the said panels from said horizontal members.

2. An apparatus of the class described comprising a frame including sides formed of horizontally directed members and vertically directed members, terminals formed of horizontally directed members united at one end to the vertical members of one of the sides, sleeves swingingly coupled to the vertical members of the other side of the frame and adapted to receive the free ends of the terminal members, and means for clamping said terminal members to the sleeves.

In testimony whereof I affix my signature in presence of two witnesses.

ARCHIE L. BOUGHAN. [L. S.]
